UNITED STATES PATENT OFFICE.

JAMES M. WILSON, OF CANTON, OHIO.

DAMPER-REGULATOR.

1,358,909.

Specification of Letters Patent. Patented Nov. 16, 1920.

Application filed May 20, 1919. Serial No. 298,480.

To all whom it may concern:

Be it known that I, JAMES M. WILSON, a subject of the King of England, residing at Canton, in the county of Stark and State of Ohio, have invented a new and useful Damper-Regulator, of which the following is a specification.

This invention relates to damper regulators for boiler furnaces, and refers more particularly to that type of damper-regulator commonly termed floating. In order that this reference may be clearly understood it is necessary to define the two classes into which, by virtue of their action, damper-regulators are divided. Damper-regulators of the simple type operate in virtue of variations of steam pressure above or below a predetermined normal point and aim to secure a maximum sensitiveness to pressure variation so that the damper is immediately closed completely or opened completely according as the pressure rises or falls from the normal. This type of apparatus may therefore be properly considered as aiming to secure uniformity of steam pressure.

Damper-regulators of the floating type constitute the second class and are so named from the fact that the damper position varies or floats between full closed and full open, according to the rate at which steam is being withdrawn from the boiler. As a certain variation in steam pressure is necessary to operate them over their entire range of movement, it will be obvious that their purpose is to maintain uniformity of furnace conditions with correspondingly increased fuel economy, rather than to maintain a uniform steam pressure between very close limits. The disturbed conditions of combustion in a boiler furnace due to being alternately fully closed and fully open, as when controlled by a damper-regulator of the simple class, have a detrimental effect on the efficiency with which the fuel is consumed, so that damper-regulators of the floating type, which seek to govern the steam output with the least disturbance of combustion conditions, represent the present advanced state of the art of boiler control.

In the class of devices known as the floating type of damper-regulator the object aimed at is attained by various means, but it is here desired to point out that no distinct effort has been made to secure other than uniform change of damper position for uni-

form change of steam pressure. This statement is made to the best of knowledge of the present state of the art, and particular reference is made to Tilden's Patent No. 60 893,284 of July 14th, 1908, page 2 line 22, etc., in which the action of his device is stated to be such that (line 28) "uniform increments of added steam pressure acting on the piston move the piston through uniform increments of distance, though uniformity throughout the range is not essential" and further (line 36) "each position of the regulating piston representing a differing steam pressure, a gradual increase in 70 steam pressure causing a gradual rise of the regulating piston, and a gradual decrease in the steam pressure permitting a gradual descent of the regulating piston." The foregoing reference is made with the purpose of clearly defining the manner in which damper-regulators of the floating type operate and to enable the operation of my device to be clearly and distinctly differentiated therefrom. 80

The object of my invention is to provide a damper-regulator of the floating type, which is so designed that the amount of closing obtained per unit increase of boiler pressure, is graded from a maximum for the first unit 85 increase, down to a smaller amount of closing for the last pressure increase within the range of the device. The invention further provides means whereby the amounts of closing or graduations of travel per unit 90 increase of pressure can be altered in their relative proportions, but with greatest effect on the initial amounts of closing. This feature enables the action of the damper-regulator to be adjusted to varying conditions of 95 boiler operation and is complementary to the peculiarly graduated control obtained by the apparatus.

My device consists essentially of a control chamber which operates valve mechanism to 100 admit or release fluid pressure from an operating cylinder, the piston rod of which is connected to the damper mechanism. Attached to and operated by the piston rod in the operating cylinder is a lever so mounted 105 on the device and connected to the valve mechanism that its control over the action of the valve results in the varying increments of damper movement already described.

My invention, therefore, to these ends, consists in the novel features and in the con-

struction, or arrangement of parts herein-after described, and pointed out in the claims following the description, due reference being had to the accompanying drawings, forming a part of this specification.

The drawings show an embodiment of the device which is at present preferred by me, although it is to be understood that the various instrumentalities of which my invention 10 consists can be variously arranged and organized and that my invention is not limited to the precise arrangement and organization of these instrumentalities as herein shown and described.

15 The invention thus set forth in general terms is illustrated in the accompanying drawings forming part hereof, in which—

Figure 1 is a perspective view of a damper regulator embodying the invention.

20 Fig. 2, a vertical sectional view of the same; and

Fig. 3, a diagrammatic view showing the movement of the compensating lever.

25 Fig. 4 is a sectional view of the three-way valve and the members operatively connected thereto.

A practical embodiment of the invention is disclosed in the accompanying drawings, forming a part of this specification in which 30 similar numerals of reference indicate corresponding parts throughout the several views.

The control chamber is indicated by the numeral 1 and contains the piston 2 which is 35 mounted therein for vertical reciprocation and carries the bracket 3 which is rigidly attached thereto. A coil spring 4 is interposed between the piston and the lower head 4', which is adjustably mounted within the 40 tubular spacing member 5 upon the upper end of which is supported the chamber 1, the lower end of said tubular member being mounted upon the base plate 6. The tension upon the coil spring 4 may be regulated by 45 adjusting the head 4'.

A pressure supply pipe 7 is connected to the boiler and provided with a branch pipe 8, which leads to the control chamber. A three-way valve 9 is mounted upon the supply pipe and connected by means of the pipe 10 with the operating cylinder 11, which is 50 also mounted upon the base plate 6. The cylinder 11 is provided with a piston 12, the piston rod 13 thereof having a block 14 rigidly connected to its upper end, said block being provided with a post 15, to which is 55 pivotally connected one end of the compensating lever 16, the other end thereof being provided with a roller 17 mounted for reciprocatory movement within the slot 18 of the guide block 19, said guide block being provided with a boss 20. This construction causes the free end of the compensating lever to move in a straight substantially horizontal line and permits the other end of the 60

compensating lever to move vertically when operated by the piston rod 13.

An upwardly extending flange 21 is provided upon the head of the controlling chamber and a screw 22 connects the boss 20 of 70 the block 19 to said flange. The guide block 19 may be adjusted to the desired angle and is then fixed to the flange 21 by tightening the screw 22.

A drain pipe 23 connects the exhaust outlet of the three-way valve 9 with the lower end of the control cylinder 11. An arm 24 is fixed upon the compensating lever 16 intermediate to the ends thereof and a link 25 pivotally connects said arm with one end of 80 a floating lever 26, which lever is pivoted at 27 to the upper end of the bracket 3 carried by the piston 2. The other end of the lever 26 is provided with a slot 28, which engages a stud 29 mounted upon the free end of the 85 lever 30, which lever is fixed to the spindle 31 of the three-way valve 9.

A flexible connection such as a chain or cord 32 is connected in any suitable manner such as by the hook 33, to the upper end of 90 the piston rod 13 and passes over suitable pulleys 34 and connects with the control lever 35 of the damper 36, a counter-weight 37 being located upon the extremity of the flexible member 32 tending to normally hold 95 the damper open.

The manner in which the device operates and the novel nature of the damper control resulting therefrom will now be described. Water under boiler pressure enters the pipe 100 7 and passing through the pipe 8 to the control chamber 1 builds up pressure which tends to force the piston 2 downward against the spring 4. This spring is provided with suitable means for adjusting it to balance 105 the boiler pressure and it is also so proportioned that when the boiler pressure rises above a predetermined point, it will yield through a suitable distance so that for a given increase of, say, one pound pressure 110 per square inch, a definite downward movement of the piston 2 is obtained.

By means of the bracket 3 this movement of the piston 2 is conveyed to the pivoted lever 26 and during the cycle of operations 115 causes it to float up and down with a similar effect on the damper position, thus giving rise to the conventional term, floating type.

Assuming the various parts would be in the position shown in Fig. 1 with the piston rod 13 fully extended, the damper 36 fully open and the piston 2 in the control chamber at the upper end of its travel and the three-way valve 9 closed:—Downward movement of the piston 2 through a given 125 distance will cause the pivotal point 27 of the floating lever 26 to move similarly. As the piston rod 13 remains stationary while the three-way valve 9 is closed, the compensating lever 16 must likewise remain sta- 130

tionary so that the link end of the floating lever 26 which is connected to the compensating lever by the link 25 and arm 24 will also remain stationary and thus cause the 5 downward movement of the pivotal point 27 to be imparted to the valve control lever 30 in a multiplied degree according to the proportions of the lever 30 and the floating lever 26.

10 This downward movement of the valve lever 30 rotates the three-way valve 9 so that connection is made from the pipe 7 through the pipe 10 to the upper end of the cylinder 11 admitting the boiler pressure 15 against the upper side of the piston 12 and thus allowing the boiler pressure to move the piston rod 13 downward so as to raise the counter-weight 37 and move the damper 36 toward the closed position. As 20 the piston rod 13 descends it carries the pivot block 14 and the outer end of the compensating lever with it so that the arm 24 and link 25 depress the link end of the floating lever 26 and cause its slotted end to raise 25 the valve control lever 30 and close the three-way valve 9, thus arresting the motion of the piston rod 13 and limiting the amount of its movement to a point which is determined by the distance through which 30 the piston 2 was depressed by the increase of boiler pressure.

Further increase of boiler pressure will result in similar distances through which the piston 2 will be forced downward 35 against the increasing resistance of the spring 4, resulting in further downward movement of the piston rod 13 with accompanying depression of the link end of the floating lever 26 and corresponding changes 40 in position of the damper 36, through the cycle of operations above described. Continued increase in pressure will therefore result in the damper being moved to the closed position, and decrease in pressure will 45 conversely result in the damper being returned to its opened position.

As a result of pressure decrease the piston 2 will rise under pressure of the spring 4 and raise the pivotal point of the floating 50 lever so that the movement of the three-way valve is reversed and connection made between the pipe 10 and the pipe 23 allowing the water in the cylinder 11 to be exhausted as the piston rod 13 is raised by 55 the counter-weight 27. The various positions assumed by the piston rod 13 while pressure is decreasing correspond with those for similar pressures while increasing.

The manner in which the foregoing 60 mechanism enables graduated decreases of damper travel to be obtained for uniform increases of steam pressure is shown diagrammatically in Fig. 3 in which corresponding numerals show corresponding 65 parts or the center lines thereof as referred

to in the other figures. Line A shows the floating lever in the position it occupies before the piston 2 has moved downward. Line B shows the position of the floating lever after the piston 2 has moved downward one-quarter of its travel with the resulting cycle of operations in the valve lever 30, the piston rod 13, compensating lever 16 and the link 25, the said cycle of operations returning the valve lever to its neutral position, there to await a further increase or decrease of steam pressure as the case may be.

Lines C and D show the positions respectively for one-half and three-quarters 80 travel of the piston 2 and line E shows the position of the floating lever at the full travel of the piston. The radial lines *a*, *b*, *c*, *d* and *e* indicate the points to which the upper end of the link 25 must be brought 85 to return the valve lever to the neutral position for each position A, B, C, D and E. The straight heavy dotted line indicates the position of the compensating lever 16 for the position B when its free end is guided 90 horizontally in the guide slot 18. The distance *A'*—*B'* is therefore the amount of closing obtained on the damper, due to the position of the floating lever being changed from B to B. Similarly the distance *B'*—*C'* 95 is obtained from the floating lever moving from B to C, *C'*—*D'* by the floating lever moving from C to D, *D'*—*E'* by floating lever moving from D to E. The curved heavy dotted line shows the path of travel of the 100 upper end of the link 25 as it passes through the radial loci *a*, *b*, *c*, *d* and *e*. If now the guide block 19 be inclined to the position shown by 19^a and the path of the upper end of the link 25 plotted out as already 105 described it will be found that the distances *A'*—*B'*—*C'*—*D'*—*E'* are altered; *A'* to *B'* is increased while the remainder are decreased approximately in proportion, thus 110 making the device more sensitive in operation for the first quarter travel of the piston 2. The straight heavy line shows position of the compensating lever at *B*² which results from the floating lever being moved to the line B while the free end of the compensating lever is moving up the inclined path of the guide block. The remaining corresponding positions are indicated by similar letters with the numeral 2. The full 115 curved line showing the movement of the upper end of the link 25 is now seen to follow the radial line *a*, very closely, and by virtue of so doing delays the downward travel of the link until such time as the curve begins to leave the radial line *a*. Although the full curve and the dotted curve cross the radial line *b* near each other the inclined position 19^a causes the compensating lever to travel farther down, *i. e.* from 120 *B*¹ to *B*² before it brings the floating 125 130

lever to the position B. The mechanism operates in exactly the reverse manner when pressure is dropping from the maximum and the floating lever assumes the positions 5 E, D, C, B, A respectively.

Consideration of the foregoing will result in it being understood that while the device acts directly on the damper its influence thereon is entirely with the view of 10 controlling the furnace conditions gradually and not by uniform increments of damper closure for equal increases in steam pressure. The method of control resulting from this operation of the mechanism allows the

15 furnace to be more completely brought under control by the damper for the first unit increase of steam pressure than is possible with a damper regulator of the uniform floating type. At the same time the close 20 control of steam pressure obtained by damper regulators of the simple type is more nearly approached and a desirable combination of the good features of both types is obtained.

25 In so far as I am aware I am the first to provide means for obtaining a gradually decreasing amount of travel of the piston rod which operates the damper for uniform increases of steam pressure and it will 30 be apparent that in accordance with the present invention, means are provided whereby this novel method of automatic damper control is rendered practicable. It will be further apparent that I have devised a new 35 and useful construction of regulating and controlling device, which while I have described and shown a practical embodiment, it is understood is susceptible of modification without departing from the spirit of 40 the invention or the scope of the claims.

I claim:—

1. A damper regulator including a control chamber, a pipe operatively connecting the control chamber with the boiler, an operating cylinder adapted to operate with boiler pressure, a valve controlling admission of boiler pressure to said operating cylinder, a piston and piston rod mounted in said cylinder and operatively connected to 50 the damper and means whereby the operation of the valve is variably governed by the piston rod.

2. A damper regulator including a control chamber, a pipe operatively connecting the control chamber with the boiler, an operating cylinder adapted to operate with boiler pressure, a valve controlling admission of boiler pressure to said operating cylinder, a piston and piston rod mounted in said cylinder and operatively connected to the damper and a floating lever controlling the valve and operatively connected with the piston rod whereby the operation of the valve is 60 variably governed by the piston rod.

65 3. A damper regulator including a con-

trol chamber, a pipe operatively connecting the control chamber with the boiler, an operating cylinder adapted to operate with boiler pressure, a valve controlling admission of boiler pressure to said operating cylinder, 70 a piston and piston rod mounted in said cylinder and operatively connected to the damper, a compensating lever connected to the piston rod and a floating lever controlling the valve and operatively connected to the compensating lever whereby the operation of the valve is variably governed by the piston rod.

4. A damper regulator including a control chamber, a pipe operatively connecting the control chamber with the boiler, an operating cylinder adapted to operate with boiler pressure, a valve controlling admission of boiler pressure to said operating cylinder, 80 a piston and piston rod mounted in said cylinder and operatively connected to the damper, a floating lever operatively connected to the control chamber and controlling the operation of the valve, a compensating lever connected to the piston rod, and 90 means operatively connecting the floating lever to the compensating lever whereby the operation of the valve is variably governed by the piston rod.

5. A damper regulator including a control chamber, a pipe operatively connecting the control chamber with the boiler, an operating cylinder adapted to operate with boiler pressure, a valve controlling admission of boiler pressure to said operating cylinder, 95 a piston and piston rod mounted in said cylinder and operatively connected to the damper, a movable bracket operated by the control chamber, a floating lever fulcrumed upon said bracket and controlling 100 the valve, a compensating lever connected to the piston rod and means operatively connecting the floating lever to the compensating lever whereby the operation of the valve is variably governed by the piston rod. 110

6. A damper regulator including a control chamber, a piston located therein, a pipe operatively connecting the control chamber with the boiler, an operating cylinder adapted to operate with boiler pressure, a valve 115 controlling admission of boiler pressure to said operating cylinder, a piston and piston rod mounted in said operating cylinder and operatively connected to the damper, a bracket carried by the piston in the control chamber, a floating lever fulcrumed upon said bracket and controlling the operation of the valve, a compensating lever connected to the piston rod and means operatively connecting the compensating lever and floating 120 lever whereby the operation of the valve is variably governed by the piston rod.

7. A damper regulator including a control chamber, a pipe operatively connecting the control chamber with the boiler, an operat- 125

ing cylinder adapted to operate with boiler pressure, a valve controlling admission of boiler pressure to said operating cylinder, a piston and piston rod mounted in said cylinder.

5 der and operatively connected to the damper, a compensating lever pivotally connected at one end to the piston rod, a guide block within which the other end of the compensating lever is slidably mounted and means
10 operatively connecting the valve with the compensating lever whereby the operation of the valve is variably governed by the piston rod.

15 8. A damper regulator including a control chamber, a pipe operatively connecting the control chamber with the boiler, an operating cylinder adapted to operate with boiler pressure, a valve controlling admission of boiler pressure to said operating cylinder, a
20 piston and piston rod mounted in said cylinder and operatively connected to the damper, a compensating lever pivotally connected at one end to the piston rod, a guide block within which the other end of the compensating lever is slidably mounted and means operatively connecting the valve with the compensating lever whereby the operation of the valve is variably governed by the piston rod, and means for adjusting said guide block to various angles.

30 block to various angles.

9. A damper regulator including a control chamber, a piston located therein, a pipe operatively connecting the control chamber with the boiler, an operating cylinder adapted to operate the boiler pressure, a valve controlling admission of boiler pressure to said operating cylinder, a piston and piston rod mounted in said operating cylinder and operatively connected to the damper, a bracket carried by the piston in the control chamber, a floating lever fulcrumed upon said bracket and controlling the operation of the valve, a compensating lever connected to the piston rod at one end, a guide block within which the other end of the compensating lever is slidably mounted and means operatively connecting the compensating lever and floating lever whereby the operation of the valve is variably governed by the piston rod.

10. A damper regulator including a control chamber, a piston located therein, a pipe operatively connecting the control chamber and the boiler, an operating cylinder adapted to operate the boiler pressure, a valve controlling admission of boiler pressure to said operating cylinder, a piston and piston rod mounted in said operating cylinder and operatively connected to the damper, a bracket carried by the piston in the control chamber, a floating lever fulcrumed upon said bracket and controlling the operation of the valve, a compensating lever connected to the piston rod at one end, a guide block within which the other end of the compensating lever is located, a lever connected to the piston rod and the compensating lever, and a lever connected to the piston rod and the guide block.

sating lever is slidably mounted and a link pivotally connecting the compensating lever and the floating lever whereby the operation of the valve is variably governed by the piston rod.

11. A damper regulator including a control chamber, a pipe operatively connecting the control chamber with the boiler, an operating cylinder adapted to operate with boiler pressure, a valve controlling admission of boiler pressure to said operating cylinder, a piston and piston rod mounted in said cylinder and operatively connected to the damper, a compensating lever pivotally connected to the piston rod, a guide block within which the other end of the compensating lever is slidably mounted and a floating lever controlling the valve and operatively connected to the compensating lever whereby the operation of the valve is variably governed by the piston rod. 75 80 85

12. A damper regulator including a control chamber, a pipe operatively connecting the control chamber with the boiler, an operating cylinder adapted to operate with boiler pressure, a valve controlling admission of boiler pressure to said operating cylinder, a piston and piston rod mounted in said cylinder and operatively connected to the damper, a floating lever operatively connected to the control chamber and controlling the operation of the valve, a compensating lever pivoted at one end to the piston rod, a guide block within which the other end of the compensating lever is slidably mounted and means operatively connecting the floating lever to the compensating lever whereby the operation of the valve is variably governed by the piston rod. 90 95 100

13. A damper regulator including a control chamber, a pipe operatively connecting the control chamber with the boiler, an operating cylinder adapted to operate with boiler pressure, a valve controlling admission of boiler pressure to said operating cylinder, a piston and piston rod mounted in said cylinder and operatively connected to the damper, a movable bracket operated by the control chamber, a floating lever fulcrumed upon said bracket and controlling the valve, a compensating lever pivotally connected at one end to the piston rod, a guide block within which the other end of the compensating lever is slidably mounted and means operatively connecting the floating lever to the compensating lever whereby the operation of the valve is variably governed by the piston rod. 105 110 115 120

14. A damper regulator including a control chamber, a pipe operatively connecting the control chamber with the boiler, an operating cylinder adapted to operate by fluid pressure, a valve controlling the admission of fluid pressure to the cylinder, a piston and piston rod mounted in the cylinder and 130

operatively connected to the damper and means whereby the operation of the valve is variably governed by the piston rod.

15. A damper regulator including a control chamber, a pipe operatively connecting the control chamber with the boiler, an operating cylinder adapted to operate with fluid pressure, a pipe operatively connecting said operating cylinder with a source 10 of fluid pressure, a valve in the last named

pipe controlling the supply of fluid pressure to said cylinder, a piston and piston rod mounted in said cylinder and operatively connected to the damper and means whereby the operation of the valve is variably governed by the piston rod. 15

In testimony that I claim the above, I have hereunto subscribed my name.

JAMES M. WILSON.
